(54) **WATER WHEEL**

(76) Inventor: **William Merrill**

William M. Morell
Petitioner

The Schedule referred to in this Petition Patent and making part of the same containing a description in the words of the said William Morell himself of his improvement in the construction of a water wheel.

To all to whom these presents shall come
Be it known that I William Morell of Randolph in the County of Putney and State of this have invented a new and useful improvement in constructing and making and using a waterwheel and that the following is a full and exact description of the construction and operation of the said waterwheel as invented or improved by me. The wheel is formed by shaft and buckets. The shaft is made of a tree large enough to compose a knob or hub two feet in diameter, to which the buckets are attached. The remainder of the shaft turned down to ten inches diameter. Five buckets (or more) form the wheel (or circle) the buckets may be made of wood or metal in a circular form with a square shoulder in the inside near the center (parallel with shaft) also a small notch in the outside to serve as a lock or for as which the adjoining ^{knob} caps on. The buckets three and half inches thick & eleven inches long, four inches of which is attached to the knob leaving, say, nine for some use one inch at the end opposite the knob of the wheel to support to the adjoining bucket. Gouges to be cut in each bucket say, inches in length parallel with the shaft and two and half inches wide at the inside and two inches wide at the outside and cut in a circular form so as to give the water an easy passage. The buckets are to be fixed to the knob and a band around each end of the buckets ($\frac{3}{4}$ inch wide at the end the water enters) The wheel may be made with one or more sets of buckets or wheels on a shaft. It operates on the reaction principle and may be used on a perpendicular, or horizontal shaft or a shaft sloping to any degree that may be necessary to accommodate the machine which.

which is to propel. The water enters the eye of the wheel (all round the shaft) and discharges at the sides. The floom or Pandstock must be made suitable for the number of wheels (or sets of buckets) used on a shaft. And a wheel may be placed within the floom or fastened to the gate hoisting below (give full draft of water into the wheel) thus the wheel will be surrounded with water which will prevent freezing in winter or drying in summer. There must be a tunnel made of thick plank and placed at the end of each wheel or set of buckets to convey the water into them. The proportion of water into the wheel to that out at the eyes must be six to one. This wheel will run under the surface of water with equal rapidity as if above water surface. It may also be placed under the end of the floom or at the side the accompanying draft fully shown.
